UNITED STATES PATENT OFFICE.

OSCAR A. LANE, DUKE GUICE, AND HERMAN P. DOHRMEIER, OF GREENVILLE,
ALABAMA.

CRATE OR BOX.

1,137,407.

Specification of Letters Patent. Patented Apr. 27, 1915.

Application filed August 27, 1914. Serial No. 858,980.

To all whom it may concern:

Be it known that we, OSCAR A. LANE, DUKE GUICE, and HERMAN P. DOHRMEIER, citizens of the United States, residing at 5 Greenville, in the county of Butler and State of Alabama, have invented certain new and useful Improvements in Crates or Boxes, of which the following is a specification.

10 The present invention relates to improvements in foldable or collapsible crates or boxes.

An important object of the invention is to provide a collapsible crate or box, which 15 may be quickly and conveniently collapsed or assembled, and the cover or lid thereof locked in the closed position.

A further object of the invention is to 20 provide a crate or box of the above mentioned character which is simple in construction, inexpensive to manufacture, strong, durable and highly convenient in use.

A further object of the invention is to 25 provide simple and inexpensive means to securely detachably lock the cover or lid in the closed position when the box or crate is assembled.

Other objects and advantages of the invention will be apparent during the course 30 of the following description.

In the accompanying drawings forming a part of this specification and in which like numerals are employed to designate like parts throughout the same, Figure 1 is a 35 side elevation of a crate or box embodying our invention, Fig. 2 is an end elevation of the same, Fig. 3 is a central longitudinal sectional view of the same, Fig. 4 is a plan view of the same, Fig. 5 is an edge elevation 40 of the sides and ends collapsed, Fig. 6 is a plan view of the sides and ends distended with the top and bottom removed, and, Fig. 7 is a fragmentary bottom plan view of one end of the cover or lid.

45 In the drawings, wherein for the purpose of illustration is shown a preferred embodiment of the invention, the numeral 10 designates sides as a whole, comprising preferably spaced strips 11, which are preferably vertically arranged, the same providing suitable ventilation. Preferably arranged upon the outer sides of the vertical strips 11 adjacent the upper and lower ends thereof, are preferably substantially horizontally ar-

ranged reinforcing longitudinal members or 55 bars 12, rigidly attached thereto by any suitable means.

The numeral 13 designates ends, as a whole, comprising preferably vertical spaced strips 14 providing suitable ventilation. Arranged upon the inner sides of the strips 14 of the ends 13 are transverse horizontal reinforcing members or bars 15, attached thereto by any suitable means. Reinforcing strips 16 are preferably secured to the outer 65 side of the end strips 14, adjacent the upper and lower ends thereof and are attached thereto by pins or nails 17, preferably entering the material of the transverse reinforcing members or bars 15. As more clearly 70 shown in Figs. 1 and 2, the lower transverse reinforcing members or bars 15 are disposed below and adjacent the longitudinal reinforcing bars or members 12, while the upper reinforcing transverse members or bars 15 75 are arranged above and adjacent the upper longitudinal reinforcing members or bars 12. The adjacent ends of the transverse and longitudinal members or bars 12 and 15 are connected by pivot elements 18, more 80 clearly shown in Fig. 5, whereby the ends and sides, when the top and bottom are removed, may be folded or collapsed, as shown.

The numeral 19 (see Fig. 3) designates the floor or bottom of the box or crate, the 85 same being adapted to be removably mounted within and between the sides and ends. This floor or bottom is preferably formed of longitudinal transversely spaced strips 20 affording suitable ventilation, the same 90 being connected near and spaced from the ends thereof by transverse strips 21, rigidly secured to the lower surface thereof, as clearly shown in Fig. 3. When the floor or bottom 19 is in place, the ends thereof 95 lie upon and are supported by transverse reinforcing members or bars 15, as clearly shown in Fig. 3.

The numeral 22 designates a removable top or lid, formed of transverse spaced 100 strips 23, affording suitable ventilation. These transverse strips 23 are secured together by longitudinally extending strips 24, rigidly attached to the lower or inner surface of the transverse strips 23, and 105 adapted to be arranged inwardly of and adjacent the upper longitudinal reinforcing members or bars 12, to engage therewith and

prevent improper lateral movement of the cover or lid with respect to the body portion of the box or crate. Attention is called to the fact that corresponding ends of the longitudinal strips 24, project for substantial distances beyond the end of the top or lid, whereby they may readily be inserted below the adjacent upper transverse reinforcing member or bar 15, to hold one end of the cover against upward movement with respect to the body portion of the box. Means are provided to securely detachably lock the opposite end of the cover or lid in the closed position, the same preferably comprising a swinging latch-strip 25, pivoted to the upper or outer surface of the top or lid 23, as shown at 26. The short end of the pivoted latch-strip is adapted to be passed beneath the adjacent transverse reinforcing member or bar 15, which may be readily accomplished by depressing that end of the latch-strip and the lid or cover, the lid or cover being formed suitably flexible for that purpose, and simultaneously swinging the free end of the latch-strip 25 inwardly, with respect to the lid or cover. If desired the opposite end of the latch-strip 25 may be inserted beneath the opposite transverse upper reinforcing member or bar 15, but we found that this is ordinarily unnecessary.

In the use of the box or crate, when the same is assembled, it may be readily collapsed, by removing the top or lid, and floor or bottom, the sides and ends then being adapted to be folded or collapsed upon each other, as clearly illustrated in Fig. 5. The top and bottom may then be placed upon these collapsed ends and sides, whereby the entire box will occupy very little space for the purpose of shipment or the like. In assembling the box for use, the sides and ends are first distended, as shown in Fig. 6. The floor or bottom 19 is first placed in the operative position, with its opposite ends engaging the transverse lower reinforcing members or bars 15. This having been done, the crate or box may be filled with the desired material, subsequently to which the cover 22 may be placed in position, and locked in the closed position by means of the latch-strip 25, as hereinabove described.

It is to be understood that the form of the invention herewith shown and described is to be taken as a preferred example of the same, and that various changes in the shape, size, and arrangement of parts may be resorted to without departing from the spirit of the invention or the scope of the subjoined claims.

Having thus described our invention what 60 we claim is:—

1. A crate or box of the character described, comprising sides having exterior longitudinal reinforcing members, ends having interior transverse reinforcing members 65 disposed above and below the longitudinal reinforcing members and pivotally connected thereto whereby the ends are adapted to be swung longitudinally of the sides, a floor removably mounted within and between the 70 sides and ends and having its opposite ends engaging and supported by the lower transverse reinforcing members of the ends, a cover removably mounted upon the upper longitudinal reinforcing members of the 75 sides and carrying upon its lower surface longitudinally extending members projecting at one end beyond the corresponding end of the cover to be inserted beneath the adjacent transverse upper reinforcing member 80 of the corresponding end, and a latch-strip pivoted to the side of the cover and adapted to have one end thereof swung to a position beneath the adjacent upper transverse reinforcing member of the corresponding end. 85

2. A crate or box of the character described, comprising sides having exterior longitudinal reinforcing members, ends having interior transverse reinforcing members disposed above and below the longitudinal 90 reinforcing members and pivotally connected thereto whereby the ends are adapted to be swung longitudinally of the sides, a floor removably mounted within and between the sides and ends and having its opposite ends 95 engaging and supported by the lower transverse reinforcing members of the ends, a cover removably mounted upon the upper longitudinal reinforcing members of the sides and carrying upon its lower surface 100 longitudinally extending members projecting at one end beyond the corresponding end of the cover to be inserted beneath the adjacent transverse upper reinforcing member of the corresponding end, and a latch-strip 105 pivoted to the outer side of the lid and adapted to have its opposite ends swung to positions beneath the upper transverse reinforcing members of the ends to detachably lock the cover. 110

In testimony whereof we affix our signatures in presence of two witnesses.

OSCAR A. LANE.

DUKE GUICE.
